Primary Examiner — Darlington Ly

(57) **CLAIM**

The ornamental design for a bicycle as shown and described.

DESCRIPTION

1. Bicycle

1.1 is a top-front-right side perspective view of a bicycle embodying our new design;

1.2 is a top-rear-left side perspective view thereof;

1.3 is a right side view thereof;

1.4 is a left side view thereof in a folded state;

1.5 is a rear view thereof in a folded state;

1.6 is a right side view thereof in a folded state; and

1.7 is an enlarged and partial perspective view thereof.

The characteristic features of the design lie in the shape of the bicycle.
